UNITED STATES PATENT OFFICE.

EDWIN MORVAL MULLIN, OF BROOKLYN, NEW YORK.

FOLDABLE DISPLAY RACK.

Application filed November 21, 1925. Serial No. 70,661.

This invention relates generally to foldable stand racks, but specifically has to do with a foldable display rack and shelf combined therewith for exhibiting wall paper samples contained in a stand book.

An important object of the invention resides in the production of a device of the above character which comprises a complete unit and which opens and closes with a single operation.

Another object of the invention is to provide a foldable rack with a tiltable section at the top thereof, said section operating to assume an angle for the purpose of imparting a "roll" to the stand book and thus giving a high light at this point for exhibiting the texture, color and sheen of the various papers in a manner that emphasizes their full decorative value.

A further object resides in the provision of means in the form of a shelf which coacts with the component parts of the rack to form a rest for the leaves of the book and for other purposes as will appear herein-after.

A still further object of the invention is to provide means associated with the supporting frame of the rack and the tiltable section for limiting the angular positioning of the latter with respect to the former.

With these objects in view, together with others which will appear as the description proceeds, the invention resides in the novel formation, combination and arrangement of parts all as will be described more fully hereinafter, illustrated in the drawings and particularly pointed out in the claims.

Referring to the drawings:

Figure 1 is a rear elevation of the rack in closed position, certain parts being broken away to show the relation of certain pivoted members.

Fig. 2 is a central longitudinal sectional view illustrating the rack partially unfolded.

Fig. 3 is a view like unto Fig. 2, but showing the rack in an advance stage of unfolding.

Fig. 4 is a side elevation of the rack in set-up position; and

Fig. 5 is a similar view but illustrating the function and purpose of the tiltable section.

Referring now more particularly to the accompanying drawings wherein like char-

acters of reference denote similar parts throughout the several views, let 10 denote the supporting frame or member of my improved stand rack. This supporting frame 10 comprises front and rear side members 11 and 12 respectively, pivoted at their upper ends by means of a pin 13, as clearly shown in the drawings. As observed in Fig. 1, there are two front and rear side members, each pair being held in spaced parallel relation by means of the cross-pieces or cleats 14 and 15 respectively.

The tiltable section 16 of my novel rack consists of upwardly extending members 17, having their lower ends pivoted between 70 the said side members 11 and 12, (see Fig. 1), while their upper ends are connected by a cross-piece 18.

The shelf portion of my rack, denoted generally by the numeral 19, also comprises side members 20, having their inner ends pivoted to the upper portions of said members 17, as at 21, and are held in spaced parallel relation by means of cleats 22.

Means for bracing said supporting frame 80 10 and said shelf 19 is provided in the form of braces 23, each of said braces comprising the parts 24 and 25 and held in spaced parallel relation by means of the cross-pieces 26 and 27.

From the foregoing it will be seen that my rack embodies essentially the supporting frame 10, the tiltable section 16, the shelf 19 and the braces 23, all of which being suitably connected to produce a rack capable 90 of folding and unfolding in a manner to be presently described in detail.

Passing now to the unfolding of the rack to the position shown in Fig. 4, let us consider said rack in the folded condition as 95 noted in Fig. 1. Here the component parts are nested substantially within the front side members 11, and the whole rack as regards thickness, is equal in width to said members 11. Each of the parts are so arranged, when being folded that they slide by one another and no interference with each other is encountered. For instance, for the sake of a clear understanding, Figs. 2 and 3 have been introduced to illustrate two steps in setting up the device, though it should be remembered that in actual practice but one operation is necessary to accomplish this purpose. In the first step the shelf portion 19 is raised upwardly, whereupon the part 25 of said 110

brace 23, which is pivoted to the side members 20 of the shelf 19, emerges from its folded position, as shown in Fig. 2, the inner end thereof, carrying the pin 29, moving downwardly until said pin 29 reaches the bottom of slot 30 in the other part 24 of the brace.

During the second step the shelf continues its upward movement and the part 25 now exerts a pull on the part 24 of the brace 23, the latter part assuming the position indicated by Fig. 3. The lower end of said part 24 is pivoted at 31 to a block 32, carried by the cross piece 14 of said side members 11, and intermediate its ends is provided with a pin 33, operating in a slot 34 in said side member 12 to cause the latter to emerge from its nested position, as clearly shown in Fig. 3.

The operation above described is continued, the pin 29 in the meanwhile riding to the upper end of said slot 30 in the part 24, causing said pin 33 to ride down the slot 34 in the side member 12 until the rack is in the set-up position as indicated in Fig. 4. The pin 29 slips to the base of said slot 30 and thus supports the shelf 19.

In Fig. 1, certain of the cleats 22 carried by the shelf 19 have been broken away in order that the relative folded positions of parts 24 and 25 of said brace 23 may be readily understood.

In this figure it will be observed that the side members 20 are positioned relatively close together in parallel relation in order that they may slide by the part 25, and this is accomplished by means of insert blocks 35 carrying the shelf pivoting means 21, as hereinbefore pointed out.

The bracing means and shelf portion of my rack are of utmost importance in that they both bespeak an advance in the art, when one considers the usual type of display rack, which comprises but a front portion having a hinged supporting means, the stand book in this case being nailed to the top of the front portion, and the individual papers in said book being thrown back and falling over the top of the front portion. In my device the supporting frame is positively held in locked position and the leaves of the stand book B, carried by the cross piece 18, are neatly piled upon the shelf portion whereby suitable notations as to selection of various papers and the customer's order may be noted in an easy and efficient manner. Obviously the returning of individual papers which have been thrown over the old-style rack, for another observation by the customer, necessitates the bending over to reach down and lift the papers over the top. In my improvement the salesman standing beside the rack, may easily turn back the individual papers for further scrutiny by the prospective purchaser. This is a feature of importance.

Probably the outstanding feature of my invention resides in the tiltable section 16, which is shown in operative position in Fig. 5. In Fig. 4, we left the rack as it would ordinarily appear in the store, but in said Fig. 5 we consider the device now in actual use to a point of highest efficiency. Considering the tiltable section now, it will be noted in Fig. 4 that the side member 17 coincides with the side members 11 of the supporting frame 10, so that in elevation the former appears to be but a continuation of said members 11. However, this is not true, but is only held in this position by means of a pin 37 striking against an upstanding pin 38 in the supporting frame. A second pin 39 rises from said supporting frame and when said tiltable section is bent or inclined rearwardly, as shown in Fig. 5, this pin 39 and pin 37 cooperate to maintain said section in the illustrated position.

Obviously my device would function as a displaying means if no tilting means were provided, but this disadvantage accrues. Let us assume the device continues in the form shown in Fig. 4 and the papers are thrown rearwardly onto the shelf until but a few papers remain resting on the front section. It is now apparent that the bent-up condition of the papers as noted at C would conceal a goodly portion of the tops of the papers on exhibition and in all likelihood would require some sort of staying means else the entire pile of papers on the shelf return to the papers remaining on the front portion. To this end I have arranged a tiltable section in order, first, that the weight of the thrown-up papers may be to the left of the vertical axis of the pivoted supporting frame, and second in order that the tops of the papers on exhibition might be readily seen, and thus produce the so-called "roll" D. The advantages are numerous, the most pronounced of all being the high light at this point for exhibiting the texture, color and sheen of the various papers in a manner that emphasizes their full decorative value.

Obviously the right is reserved to make such changes and modifications that fall within the spirit of the invention and the scope of the appended claims.

I claim:

1. A foldable rack comprising a supporting frame, a shelf adapted to receive flexible sheets and a tiltable section pivotally connected to said frame and shelf, and adapted to support flexible sheets, the rearward tilt of said section positioning the roll produced in the thrown-up sheets rearward of the vertical axis of the pivotal connection between said section and frame.

2. A foldable rack comprising a supporting frame, a shelf adapted to receive flexible sheets, a tiltable section pivotally connected to said frame and shelf, and adapted to sup-

port flexible sheets, the rearward tilt of said section positioning the roll produced in the thrown-up sheets rearward of the vertical axis of the pivotal connection between said section and frame, and means for limiting the tilt of said section.

3. A foldable rack comprising a supporting frame, a shelf adapted to receive flexible sheets, a tiltable section pivotally connected to said frame and shelf and adapted to support flexible sheets, the rearward tilt of said section positioning the roll produced in the thrown-up sheets rearward of the vertical axis of the pivot connection between said section and frame, and braces pivotally connected to said shelf and said frame, each of

said braces being pivoted intermediate their ends to break into a foldable position.

4. In a foldable display rack, the combination with a supporting frame and shelf, of a tiltable section pivotally connected to said frame and shelf, said tiltable section carrying a quantity of flexible sheets and adapted to be tilted rearwardly to displace the roll produced by said sheets when in thrown-up position, to a position rearward of the vertical axis of the pivotal connection between said section and frame. 20 25

In testimony whereof I have signed my name to this specification.

EDWIN MORVAL MULLIN.
